SUPPORT STAND FOR AN OFFICE MACHINE

Joel W. Bravo, Montrose, Pa., and Paul Matwey, Binghamton, N.Y., assignors to General Aniline & Film Corporation, New York, N.Y., a corporation of Delaware

Filed Jan. 23, 1967, Ser. No. 5,527

Term of patent 7 years

(Cl. D33—3)

Fig. 1.

Fig. 2.

Fig. 3.

Fig. 4.

FIG. 1 is a front perspective view of a support stand for an office machine showing our new design;

FIG. 2 is a front elevational view thereof;

FIG. 3 is a right side elevational view thereof; and

FIG. 4 is a top view thereof.
The side of the stand not shown is like the side shown, while the back is substantially the same in appearance as the front thereof.

We claim:

The ornamental design for a support stand for an office machine, substantially as shown and described.
